Patented June 10, 1958

183,015

WATER METER

Amos B. Newbury, Murrysville, and Henning Karlby, Pittsburgh, Pa., assignors to Rockwell Manufacturing Company, Pittsburgh, Pa., a corporation of Pennsylvania

Application July 18, 1957, Serial No. 46,983

Term of patent 14 years

(Cl. D91—1)

Figure 1 is a perspective view of a water meter showing our new design;

Figure 2 is a top plan view thereof;

Figure 3 is a side elevational view thereof; and

Figure 4 is an end elevational view thereof.

The dominant features of our design reside in the portions shown in full lines.

We claim:

The ornamental design for a water meter, substantially as shown and described.
